[57] CLAIM

The ornamental design for a portion of a propeller spinner, substantially as shown and described.

DESCRIPTION

FIG. 1 is a perspective view of a portion of a propeller spinner showing my new design;

FIG. 2 is an elevational view of one side of said portion of a propeller spinner, the elevational view of the other side being substantially a mirror image thereof;

FIG. 3 is a top plan view of said portion of a propeller spinner;

FIG. 4 is a front elevational view of said portion of a propeller spinner; and

FIG. 5 is a sectional view of said portion of a propeller spinner taken on the line 5—5 of FIG. 3.
